UNITED STATES PATENT OFFICE.

PAUL BASTIEN, OF INDIANAPOLIS, INDIANA, ASSIGNOR TO BENDIX BRAKE COMPANY, OF CHICAGO, ILLINOIS, A CORPORATION OF ILLINOIS.

BRAKE.

Original application filed October 4, 1923, Serial No. 666,514. Divided and this application filed March 8, 1926. Serial No. 93,028.

This invention relates to brakes, and is illustrated as embodied in an internal expanding brake for an automobile wheel. An object of the invention is to provide a novel and simple, but efficient, connection between a pair of brake shoes or other friction devices so arranged that one operates the other through the connection. Preferably one shoe or other device is anchored, as for example by being mounted on a fixed pivot at one end, and is operated, as described, through the connection.

In one desirable arrangement, the novel connection includes a lever, which may be a bellcrank lever fulcrumed between the axis and the circumference of the brake drum, and which is shown pivotally connected at its ends to the shoes.

Other features of the invention relate to a novel arrangement of return springs for the anchored shoe, and to other novel combinations of parts and desirable particular constructions, all of which will be apparent from the following description of one illustrative embodiment shown in the accompanying drawing, in which:

Fig. 1 is a vertical section showing one wheel and its brake in inside elevation; and Fig. 2 is a rear elevation of the wheel and brake, broken away to show the brake in transverse vertical section on the line 2—2 of Fig. 1.

In the arrangement illustrated, a wheel 10, rotatably mounted on an axle including a drive shaft 12 and a housing 14, carries a brake drum 16. Within the drum are friction devices, such as arcuate shoes 18 and 20, shoe 18 being anchored on a pivot or fixed anchor 22 on a support 24 carried by housing 14.

Shoe 20, or its equivalent, is arranged to be forced against the drum, against the resistance of a return spring 26 connected at its ends to the two shoes, by means such as a cam 28 on a shaft 30 journalled in support 24 and operated by an arm 32. The free end of shoe 20 is guided by a slot 34 embracing a pin 36 carried by support 24.

Between the adjacent ends of the shoes is a connection such as a bellcrank lever 38 fulcrumed, preferably approximately midway between the axis and the circumference of the drum, upon a fixed pivot 40. One end of this lever is pivoted, preferably by

a slot 42 embracing a pivot pin 44, to the end of shoe 20. The other end of the lever, or an equivalent part rigid with the lever, is connected by means such as a pivot 46 to the unanchored end of shoe 18.

Thus movement of shoe 20 with the drum, when the brake is applied, rocks lever 38 to force shoe 18 against the drum. Shoe 18 is shown urged away from the drum by two return springs, one spring 48 being connected directly to the shoe 18 while the other 50 is connected to shoe 20 at such an angle that it tends to act through connection 38 to swing shoe 18 away from the drum.

While one illustrative embodiment has been described in detail, it is not my intention to limit the scope of the invention to that particular embodiment, or otherwise than by the terms of the appended claims. The present application is a division of my application No. 666,514, filed October 4, 1923.

I claim:

1. A brake comprising, in combination, a drum, a pair of friction devices engageable with the drum, and a rigid lever fulcrumed between its ends between the center of the drum and its circumference, one friction device being directly pivoted to the lever and arranged to act on one end of the lever to rock the lever about its fulcrum, and the other end of the lever being directly pivoted to the other device and arranged to force the other friction device against the drum.

2. A brake comprising, in combination, a drum, a pair of shoes arranged end to end and engageable with the same zone of the drum, and a lever fulcrumed between its ends between the center of the drum and its circumference, one shoe being pivotally connected to the lever and arranged to act on one end of the lever to rock the lever about its fulcrum, and the lever also being positively connected to the other shoe and being arranged to force the other shoe against the drum.

3. A brake comprising, in combination, a drum, a pair of friction devices engageable with the same zone of the drum, and a bellcrank lever connected at its ends to said friction devices so that the one device forces the other against the drum by rocking the bellcrank lev-

4. A brake comprising, in combination, a drum, a pair of shoes engageable with the same zone of the drum, and a bellcrank lever connected at its ends to the ends of said shoes so that the one shoe forces the end of the other against the drum by rocking the bellcrank lever.
5. A brake comprising, in combination, a drum, a pair of friction devices engageable with the same zone of the drum, and a bellcrank lever pivoted directly at its ends to said friction devices so that the one device forces the other against the drum by rocking the bellcrank lever.
- 13 6. A brake comprising, in combination, a drum, a pair of shoes engageable with the same zone of the drum, and a bellcrank lever pivoted directly at its ends to the ends of said shoes so that the one shoe forces the end of the other against the drum by rocking the bellcrank lever.
7. A brake comprising, in combination, a drum, a plurality of shoes, an anchor for one shoe, a connection through which the unanchored shoe operates the anchored shoe, a spring directly connected to the anchored shoe and urging it away from the drum, and an auxiliary spring connected to the unanchored shoe and acting through the connection to urge the anchored shoe away from the drum.
8. A brake comprising, in combination, a drum, a plurality of shoes, an anchor for one shoe, a connection through which the unanchored shoe operates the anchored shoe, a spring directly connected to the anchored shoe and urging it away from the drum, and an auxiliary spring acting through the connection to urge the anchored shoe away from the drum.
9. A brake comprising, in combination, a drum, an anchored shoe and an unanchored shoe arranged end to end and engageable with the same zone of the drum, means connecting the unanchored shoe to the unanchored end of the anchored shoe and through which the unanchored shoe acts to force the anchored shoe against the drum, and a spring connected to the unanchored shoe and acting through said means to urge the anchored shoe away from the drum.
10. A brake comprising, in combination, a drum, an anchored shoe and an unanchored shoe arranged end to end and engageable with the same zone of the drum,
- means connecting one end of the unanchored shoe to the unanchored end of the anchored shoe and through which the unanchored shoe acts to force the anchored shoe against the drum, and a spring connected to the unanchored shoe near its connected end and acting through said means to urge the anchored shoe away from the drum.
11. A brake comprising, in combination, a drum, a pair of shoes arranged end to end and engageable with the same zone of the drum, and a lever connected to the end of one shoe and having a part rigid with the connected part of the lever and positively connected to the other shoe to force it against the drum.
12. A brake comprising, in combination, a drum, a pair of shoes arranged end to end and engageable with the same zone of the drum, and a lever connected to the end of one shoe and having a part rigid with the connected part of the lever and pivoted directly to the adjacent end of the other shoe to force it against the drum.
13. A brake comprising, in combination, a drum, a pair of shoes arranged end to end and engageable with the same zone of the drum, and a lever rocked by one shoe about a fulcrum between the center and the circumference of the drum and pivotally connected to the other shoe to force it against the drum.
14. A brake comprising, in combination, a drum, a pair of shoes arranged end to end and engageable with the same zone of the drum, and a lever connected to the end of one shoe and rocked about a fulcrum between the center and the circumference of the drum and having a thrust part pivoted to the other shoe and arranged to force it against the drum.
15. A brake comprising, in combination, a drum, anchored and unanchored shoes arranged end to end and engageable with the same zone of the drum, and a lever connected to the end of one shoe and rocked about a fulcrum between the center and the circumference of the drum and having a part pivotally engaging the unanchored end of the anchored shoe and arranged to force the anchored shoe against the drum.

In testimony whereof, I have hereunto signed my name.

PAUL BASTIEN.
